TRUCK BODY MOUNTED REFRIGERATION UNIT

William A. Forsty, Murrysville, Pa., and Joe R. Barnett, Minneapolis, Minn., assignors to Thermo King Corporation, Minneapolis, Minn.

Filed Apr. 19, 1971, Ser. No. 135,518

Term of patent 14 years

Int. Cl. D23—04
U.S. Cl. D23—142

FIG. 1

FIG. 2

FIG. 3

FIG. 1 is a top plan view of a truck body mounted refrigeration unit showing my new design;

FIG. 2 is a front elevational view thereof;

FIG. 3 is a side elevational view thereof, the opposite side being identical.

The rear and bottom are substantially flat and unmounted.

We claim:

The ornamental design for a truck body mounted refrigeration unit, substantially as shown and described.
